CLAIM

The ornamental design for a combined filter element and frame therefor, as shown and described.

DESCRIPTION

FIG. 1 shows a perspective view of a combined filter element and frame therefor according to the principles of the present invention;

FIG. 2 shows a front elevational view thereof, a rear elevational view not being shown as it is a mirror image of the front elevational view;

FIG. 3 shows a top plan view thereof; and,

FIG. 4 shows a right side elevational view, a left side elevational view not being shown as it is a mirror image of the right side elevational view.
